UNITED STATES PATENT OFFICE.

OTTO PROCHNOW, OF WEST ALLIS, WISCONSIN.

STRAP-SUPPORT FOR GUNS.

1,115,737.

Specification of Letters Patent.

Patented Nov. 3, 1914.

Application filed September 12, 1912. Serial No. 719,905.

To all whom it may concern:

Be it known that I, OTTO PROCHNOW, a citizen of the United States, residing at West Allis, county of Milwaukee, and State 5 of Wisconsin, have invented new and useful Improvements in Strap-Supports for Guns, of which the following is a specification.

My invention relates to improvements in strap supports for guns, with especial reference to that class of strap supports shown and described in my former application for Letters Patent of the United States, Serial No. 683047, filed March 11th, 1912, and allowed July 22, 1912.

15 The object of my present invention is to provide means for locking the winding spool with the strap extended to any desired length.

Incidentally to the above object, I also 20 provide means whereby the spool may be manually actuated and the spring illustrated in my former patent dispensed with.

In the drawings—Figure 1 is a side view of a gun embodying my invention. Fig. 2 25 is a sectional view of the winding spool and casing, removed from the gun stock, and showing also a portion of the strap partially wound thereon. Fig. 3 is a side view, partly in section, of a winding spool and casing embodying a modified form of my invention, in which a winding spring is employed. Fig. 4 is a sectional view of the same, drawn 30 to a plane exposing the winding shaft.

Like parts are identified by the same reference characters throughout the several views.

The gun stock 1 has a cylindrical casing 2 socketed therein similar to that shown and described in my former application. A winding shaft 3 extends through the casing transversely and carries a spool 4 upon which the gun supporting strap 5 is adapted to be wound. said strap extending through a peripheral opening 9 in the casing, substantially as shown and described in my former application. In the construction illustrated in Figs. 1 and 2, the projecting end 6 of the shaft is flattened and adapted to receive the head 7 of a crank arm 8. The crank arm 8 45 is formed in sections connected with each other by a hinged joint at 10, and the outer section of the arm is provided with a locking pin 11, preferably rigidly secured to the arm and adapted to engage in holes 12 formed in 50 the casing flange 13. When the pin 11 is

inserted in one of these holes 12, the crank arm 8 is locked against rotation and is also held closely to the adjacent wall of the casing 2. The pin 11 is adapted to fit snugly in the holes 12 and to bind therein by frictional contact. The hinge 10 is also preferably formed with a tight-fitting pintle, whereby an accidental swinging of one section upon the other is prevented. By manually pulling upon the pin 11, however, said pin may be withdrawn from the hole 12 in which it is engaged, and the outer section simultaneously swung to a position at right angles to the inner section, whereupon said outer section may serve as a crank handle to facilitate revolving the shaft 6 and winding spool 4. When the strap is extended or rewound upon the spool to the desired extent, the outer section of the crank arm 8 will be swung into alignment with the inner section, 75 as illustrated in Fig. 2, and the pin 11 re-engaged in one of the holes 12. The outer end of the strap being provided with a fastening 15 engaging an eye-piece 16 on the gun barrel, it is obvious that when the strap 80 is not used to support the gun from the shoulder, it will only be necessary to wind up the strap sufficiently to draw it to the position illustrated in Fig. 1, whereupon the gun may be carried over the shoulder with 85 the taut strap resting upon the shoulder, the locking pin 11 preventing any rotation of the spool and therefore preventing the strap from becoming slack. The strap will yield somewhat, however, and materially relieve 90 the shoulder from irritating pressure, such as would be exerted by the gun barrel if the strap were not used. It is obvious that the strap may be extended to any desired extent from the adjustment illustrated by full lines 95 in Fig. 1 to facilitate carrying the gun by suspending it from the shoulder, or from a wall support, or any other desired point.

By employing a jointed crank arm 8, I am enabled to use a thin and comparatively wide arm, which will lie substantially flat against the exposed wall of the casing, the pin 11 being provided with a broad flat head, which projects but little from said wall. The arm, therefore, will not catch in 100 the clothing of the user, or otherwise interfere with the ordinary use of the gun. This arrangement, however, makes it highly desirable that the arm 8 should be jointed in order that the outer section may be swung 110

outwardly to facilitate rotating the crank and also to withdraw the pin 11 from the casing holes 12.

Referring to Figs. 3 and 4, it will be observed that a strap winding spool 18 is employed, and this spool is provided at one end with an end disk 19, provided with a series of notches 20. A shaft 21 is employed similar to the shaft 3, and a casing 22 incloses the spool and is provided with a separate compartment 24, similar to that shown in my former application, and in which a winding spring 25 is located, the ends of said spring being connected with the shaft and casing respectively. A segmental locking member 26 is pivoted at 27 to the front wall of the casing and is provided with an inwardly turned lip 28, adapted to engage in any one of the notches 20 when the latter is in registry therewith. A spring 30 is preferably employed to automatically move the locking arm 26 to locking position, whenever the lip 28 registers with one of the notches 20. The locking arm 26 is provided with a lateral projection 31, which extends through an opening 32 in the exposed wall of the casing, whereby outward pressure may be applied to the projection 31 to retract locking arm 26 and withdraw lip 28 from the notch 20 in which it is engaged. As soon as the locking arm is retracted, the spring 25 will be effective to wind up the strap, but if it is desired to extend the strap, this can be done by pulling the same outwardly against the tension of the winding spring. When the desired position of strap adjustment is reached, projection 31 may be released, whereupon lip 28 will automatically reengage with one of the notches 20 and lock the spool against rotation. It will be understood that if desired, the crank arm 8 shown in Figs. 1 and 2 may be applied to the shaft 21 of Figs. 3 and 4, and used for unwinding the spring or for locking the spool. Where this is done, the locking arm 26 may be dispensed with in this

construction as well as in the construction shown in Figs. 1 and 2. Where the gun stock is thick enough so that a socket may be provided therein of sufficient depth to readily receive the casing 22, the construction shown in Figs. 3 and 4 will preferably be employed, for the reason that the surface of the casing will have no projecting parts except the slight projection of the member 31, but where the gun stock is thin and a deep casing cannot be readily employed, the construction shown in Figs. 1 and 2 will be preferred. The additional casing depth required for the reception of the spring 25 is not required for the construction shown in Figs. 1 and 2.

I claim—

1. The combination with a gun stock, of a casing socketed therein, a winding spool rotatively mounted in the casing, a gun supporting strap connected with said winding spool, a manually operated member normally parallel with one face of the casing throughout its length; said member being connected with said winding spool and having a swinging outer end portion adapted to move relatively to said casing face provided with means for locking said spool.

2. The combination with a gun stock, of a casing socketed therein, a winding spool rotatively mounted in the casing, a gun supporting strap connected with said winding spool, a manually operated member normally substantially parallel with one face of the casing throughout its length, and having a swinging outer end portion provided with means for locking said spool, said outer portion of said member being adapted to be manually actuated to release said spool and allow a readjustment of the strap.

In testimony whereof I affix my signature in the presence of two witnesses.

OTTO PROCHNOW.
